[57] CLAIM

The ornamental design for an electric water heater, as
shown and described.

DESCRIPTION

FIG. 1 is a right side elevational view of an electric
water heater, showing my new design, the left side
being a mirror image thereof;

FIG. 2 is a bottom plan view thereof;

FIG. 3 is a top plan view thereof;

FIG. 4 is a front elevational view thereof; and

FIG. 5 is a rear elevational view thereof.

FIG. 1

FIG. 2

FIG. 3

FIG. 4

FIG. 5
